UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,084, dated August 20, 1872.

Specification describing a Design for a Shawl-Pattern, invented by FREDERICK WINK, of Philadelphia, Pennsylvania.

Design for a Shawl-Pattern.

The figure in the accompanying drawing represents sufficient of a shawl-pattern to illustrate my design, the principal features of which are the two stripes A and B. The stripe A is composed of a series of parallel minor stripes, *a*, *b*, *c*, *d*, &c., the central stripe *a* and the stripes *c* being ornamented by zigzag markings, as plainly shown in the drawing, while the remaining stripes are plain. The stripe B is also composed of a series of minor stripes, some of which are plain and others ornamented, the ornamentation of the central

stripe *f* and of the narrow stripes *g* at the edges of the main stripe being of the same zigzag character as upon the stripe A.

Irrespective of the colors employed, I claim—

1. The design for the stripe A, substantially as shown and described.
2. The design for the stripe B, substantially as described and represented.
3. The design for the whole pattern, including the stripes A and B.

In testimony whereof I have signed my name to this specification in the presence of two subscribing witnesses.

FRED. WINK.
